SEWING MACHINE

Charles F. Rubel, Chicago, Ill., assignor to Union
Special Machine Company, Chicago, Ill., a cor-
poration of Illinois

Application January 3, 1942, Serial No. 425,494

13 Claims. (Cl. 112—236)

This invention relates to an improved sewing machine construction. It has particular reference to lockstitch machines and to the operation thereof in the course of tacking or locking the ends of a seam.

In the customary use of lockstitch machines, as heretofore constructed, considerable skill and experience has been required to provide a lock at the end of a seam in a neat and effective manner. The operator has been compelled to exert just the right amount of pressure upon the knee control, or other device, provided for lifting the presser bar so that the pressure of the spring acting on this bar has been relieved just sufficiently to enable appropriate manipulation of the work for tacking purposes. For proper results, this must be accomplished without actually lifting the presser foot from the work. If the presser foot is lifted from the work, the latter has a tendency to follow the needles in their upward movement with the result that "drum heading" occurs. That is to say, the needle thread loops are not correctly formed so as to be caught properly by the rotary hook, thus causing the skipping of some of the loops.

An object of the present invention has been to provide a simple construction by which tacking may be correctly and expeditiously performed by operators having little or no special skill or experience in performing this type of work. Toward this end a special presser foot construction has been provided which is simple in its use.

Other objects, features and advantages of the invention will appear from the detailed description of an illustrative form of the same which will now be given in conjunction with the accompanying drawings, in which:

Fig. 1 is a front elevation of the machine with the cover plate of the needle head removed and with a portion of the work support shown in section.

Fig. 2 is a detail view, in elevation, showing the connections between a lifting lever and the presser bar.

Fig. 3 is an enlarged detail, partly in elevation and partly in section, showing the construction of the presser foot and its connection with the lower end of the presser bar, the parts being shown in their normal, active positions for seam formation.

Fig. 4 is a view similar to Fig. 3 but shows the parts in tacking position.

Fig. 5 is an exploded, perspective view showing the details of each part of the presser foot, and

away, showing the complete machine on a reduced scale.

For purposes of illustration, the invention has been shown applied to a machine of the general type disclosed in the Christensen et al. Patent No. 2,113,572, granted April 12, 1938. Reference may be had to said patent for further details regarding the construction and operation of certain of the devices embodied in the machine, such as

10 the stitch-forming and work-feeding devices, which will be but briefly described herein.

Referring now particularly to Figs. 1 and 6, the machine comprises a base portion 10 adapted to be suitably mounted in the top of a work table 15 and providing on its upper surface a support for the work to be stitched. Secured to the base portion 10, adjacent one end, is a vertical standard 11, from the top of which projects, laterally, an overhanging arm 12 carrying a needle head 13.

20 Within the needle head a vertically reciprocable needle bar 14 is provided, this carrying one or more needles 15 at its lower end. The means for reciprocating the needle bar are not shown in the present case but are disclosed in said Christensen et al. patent.

These means are driven by suitable connections from the combined hand-wheel and pulley 16 adapted to receive power from any appropriate source. Within the base portion 10 a rotary hook 17 is provided to form a lockstitch

30 in conjunction with the needle 15. Suitable connections (not shown) are provided from the main drive shaft carrying the pulley 16 to rotate the rotary hook in synchronism with the operation of the needle. A throat plate 18 is provided in the

35 work supporting surface of the base portion 10 and the work 19 is adapted to be fed over this throat plate by means of a feed dog 20 having portions extending through the usual slots formed in the throat plate. Any suitable means, such as

40 that disclosed in said prior Christensen et al. patent, may be provided for imparting the desired four-motion feed movements to the feed dog 20.

Also mounted for vertical movement within the needle head is a presser bar 21 slidable in a bearing in the lower portion 22 of the needle head and in a bearing provided by the inner surface of a sleeve 23 having screw-threaded engagement with a portion 24 at the top of the needle head. A thumb screw 25, carried by the upper end of the sleeve 23, enables the vertical adjustment of this sleeve within the needle head frame. About midway of the length of the presser bar there is secured a block 26 which extends laterally into a slot formed in the side wall of the needle head,

55 the upper end of this slot being indicated at 27.

Fig. 6 is a side elevation, with portions broken

A spring 28, surrounding the presser bar, bears at its upper end against sleeve 23 and at its lower end against the top of the block 26. The spring thus urges the presser bar downwardly by a force which may be varied to suit particular requirements by proper adjustment of the sleeve 23.

Beneath the block 26 there is slidably mounted on the presser bar a sleeve or collar 29 having at its upper end a laterally extending arm 30 cooperating with the guide slot 27 in the side wall of the needle head. Arm 30 is parallel with and is normally spaced slightly below the arm 26 but it is adapted to be lifted into engagement with the latter arm and to be then lifted further to elevate the presser bar. For this purpose the sleeve 29 has, at its upper end, a rearwardly extending arm 31 to which is pivotally connected a link 32 having its upper end pivotally attached to a forwardly extending arm of a two-armed lever 33. This lever is attached to the frame of the machine by a pivot screw 34. A spring 35 connected to lever 33 and to a pin on the machine frame normally serves to rock the lever in a clockwise direction (Figs. 1 and 6) and maintains the arm 30 in its spaced relation to the arm 26. At this time the arm 30 rests upon the upper surface of a cam member 36 pivoted at 37 upon the needle head and adapted to be rocked manually by a lever 38. When lever 38 is lifted by the operator, the arm 30 will be raised against the arm 26 and the presser bar will then be raised to lift the presser foot, to be later described, from the work. The form of the cam member 36 is such that it will hold the presser bar in its elevated position, when desired.

To the rearwardly extending arm of the lever 33 there is connected a rod or link 39, this being preferably bent over at its upper end and inserted in a hole adjacent the end of the lever. A cotter pin may be used to hold the rod in place. At its lower end the rod 39 is connected with the rearwardly extending arm 40 of a rock member carried by a stud 41 mounted in the base member 10 of the machine. A forwardly extending arm 42 of the rock member carries a pin 43 adapted to engage the curved upper surface of a rod or arm 44 secured to a rock shaft 45 mounted on a bracket secured to the under side of the table which carries the machine. At a convenient point, the rock shaft 45 has secured thereto a downwardly extending arm 46 which carries a knee-operated member 47 adapted to be engaged by the left knee of the operator of the machine. As the knee plate 47 is shifted toward the left (Fig. 6), the shaft 45 will be rocked clockwise to rock the arms 40 and 42, as well as the lever 33, counter-clockwise, thus lifting the sleeve 29, and hence the presser bar, against the action of the spring 28.

At the lower end of the presser bar there is secured a presser foot of special construction. This presser foot has a shank 48 adapted to be secured to the lower end of the presser bar by means of a screw 49. A blocklike extension 50 of the shank has a vertically disposed opening in which is slidably mounted a stem 51 formed as an integral, upward extension of a block 52. A screw 53 secured to the upper end of the stem 51 has an enlarged head adapted to slide in an enlarged recess 54 adjacent the top of the shank extension 50. A spring 55 coiled about the stem 51 within an enlarged recess 56 at the bottom of the extension 50 urges the stem and block 52 downwardly. When the presser

bar is lifted into the position indicated in Fig. 4, the spring 55 will urge the stem 51 downwardly until the under surface of the head of screw 53 engages the bottom of the enlarged recess 54. In a transverse aperture through the block 52 there is mounted a pin 57 which serves to pivotally attach to the block a presser foot 58 of any suitable form. At the sides of the presser foot there are integral, upwardly extending ears 59 adapted to straddle the block 52 and to engage the flat, side surfaces of the extension 50 of the shank. The ears 59 are constantly engaged with the sides of the shank extension and thus prevent relative turning in a horizontal direction between the presser foot and shank. However, relative sliding movement and relative turning in a vertical plane is permitted between the presser foot and shank.

In the normal operation of the machine, the presser bar and the presser foot will assume the relationship indicated in Fig. 3. The under surface 60 of the shank will be brought against the top of the block 52, the spring 55 being compressed due to the superior strength of the spring 28. Presser foot 58 may, at this time, tilt about the pin 57 in passing over seams in the work as the latter is advanced by the feed dog 29. In general the operation will be substantially the same as if the presser foot were pivoted directly upon an integral part of the shank. When the end of the seam is reached, however, and it is desired to perform a tacking operation, the operator will press the knee against the knee plate 47 and shift the latter sufficiently to raise the presser bar into any position between that indicated in Fig. 3 and that indicated in Fig. 4. The pressure of the spring 28 will be completely offset and the presser foot will be held against the work merely by the force of the spring 55. This greatly reduced pressure will be sufficient to prevent the drum-heading evil, which the invention is intended to eliminate, but it will not interfere with the relatively free movement of the work by hand.

The operator, in utilizing the improved construction, need not shift the knee control with any particular precision. Considerable latitude is permitted in the extent of movement of this control member. It is sufficient merely to relieve or offset the pressure of the spring 28 without, in fact, lifting the presser bar at all, and it is also entirely satisfactory to lift the presser bar a substantial extent, i. e., approximately the amount of the relative movement between the shank 48 and the stem 51, permitted by the block 52 and the head of screw 53. The clearance between the shank and the head of the screw should not be taken up completely, since then the pressure of even the spring 55 would be removed from the presser foot. Of course, the presser bar may be lifted to any point intermediate the two extreme positions shown in Figs. 3 and 4. No special aptitude or experience on the part of the operator will be required to accomplish this and a substantially uniform, light pressure on the presser foot is insured for tacking purposes at all times. Whenever it is desired to disable the presser foot completely, the presser bar may be raised high enough to lift the presser foot from the work. This will be done after the clearance between the head of screw 53 and the bottom of recess 54 has first been taken up. Such lifting of the presser foot may be accomplished either by the knee control or by the lever 38.

While an illustrative embodiment of the improved sewing machine has been described in some detail, it will be understood that various changes may be made in the construction and arrangement of the parts without departing from the general principles and scope of the invention.

What I claim is:

1. In a sewing machine, a work support, a presser bar, a spring urging said presser bar downwardly, a shank attached to the lower end of said bar, a block slidably mounted on said shank, a spring urging said block downwardly on said shank, and a presser member carried by said block, said first mentioned spring being stronger than the second, said presser bar and shank being normally free to move downwardly until said first mentioned spring forces said block into its uppermost position on said shank in solid engagement with a surface thereon and retains said presser member yieldingly by the full force of said first mentioned spring against work on said support.

2. In a sewing machine, a work support, a presser bar, a spring urging said presser bar downwardly, a shank attached to the lower end of said bar, a block slidably mounted on said shank, a spring urging said block downwardly on said shank, and a presser member pivotally mounted on said block, said first mentioned spring being stronger than the second, said presser bar and shank being normally free to move downwardly until said first mentioned spring forces said block into its uppermost position on said shank in solid engagement with a surface thereon and retains said presser member yieldingly by the full force of said first mentioned spring against work on said support.

3. In a sewing machine, a work support, a presser bar, a spring urging said presser bar downwardly, a shank attached to the lower end of said bar, a presser foot shiftably mounted on said shank, and a spring urging said presser foot into one position on said shank and serving to hold said foot against work of uniform thickness on said support as the presser bar is raised slightly, said first mentioned spring being stronger than the second, said presser bar and shank being normally free to move downwardly until said first mentioned spring shifts said presser foot into a predetermined position on said shank against the action of said second spring and holds it yieldingly against the work by the action of said first mentioned spring.

4. In a sewing machine, a work support, a presser bar, a spring urging said presser bar downwardly, a shank attached to the lower end of said bar, a presser foot shiftably mounted on said shank, means limiting the movement of said presser foot relative to said shank in either direction, and a second spring urging said presser foot in one direction relative to said shank, said first mentioned spring being stronger than the second, the parts being so constructed and arranged that said first-mentioned spring serves to hold said presser foot normally at its limit of movement in a direction opposite to said one direction against the action of said second spring and to hold the presser foot yieldingly against the work by the action of said first mentioned spring.

5. In a sewing machine, a work support, a presser bar, a spring urging said presser bar downwardly, a shank attached to the lower end of said bar, a presser foot shiftably mounted on said shank, means limiting the movement of said

presser foot relative to said shank in either direction, a second spring urging said presser foot in one direction relative to said shank, said first mentioned spring being stronger than the second, the parts being so constructed and arranged that said first-mentioned spring serves to hold said presser foot normally at its limit of movement in a direction opposite to said one direction against the action of said second spring and to hold the presser foot yieldingly against the work by the action of said first mentioned spring, and means operable at will for lifting said presser bar slightly and thereby offsetting the action of said first mentioned spring, said presser foot then being urged against the work by said second spring.

6. In a sewing machine, a work support, a presser bar, a spring urging said presser bar downwardly, a shank attached to the lower end of said bar, a presser foot shiftably mounted on said shank, means limiting the movement of said presser foot relative to said shank in either direction, a second spring urging said presser foot in one direction relative to said shank, said first mentioned spring being stronger than the second, the parts being so constructed and arranged that said first-mentioned spring serves to hold said presser foot normally at its limit of movement in a direction opposite to said one direction against the action of said second spring and to hold the presser foot yieldingly against the work by the action of said first mentioned spring and means operable at will for lifting said presser bar slightly and thereby offsetting the action of said first mentioned spring, said presser foot then being urged against the work by said second spring, said last mentioned means being operable also to lift said presser foot completely from the work.

7. In a sewing machine, a work support, a presser bar, a spring urging said presser bar downwardly, a shank attached to the lower end of said bar, a presser foot shiftably mounted on said shank, means limiting the movement of said presser foot relative to said shank in either direction, a second spring urging said presser foot in one direction relative to said shank, said first mentioned spring being stronger than the second, the parts being so constructed and arranged that said first-mentioned spring serves to hold said presser foot normally at its limit of movement in a direction opposite to said one direction against the action of said second spring and to hold the presser foot yieldingly against the work by the action of said first mentioned spring, knee actuated means for lifting said presser bar slightly and thereby offsetting the action of said first mentioned spring while permitting said presser foot to be urged against the work by said second spring, and manual means for lifting said presser bar to disengage the presser foot completely from the work.

8. In a sewing machine, a work support, a presser bar, a spring urging said presser bar downwardly, a shank attached to the lower end of said bar, a carrier shiftably mounted on said shank, stop means for limiting the movement of said carrier in each direction on said shank, a second spring urging said carrier in one direction relative to the shank, and a presser foot pivotally mounted on said carrier, said first mentioned spring being stronger than said second spring, the parts being so constructed and arranged that said first-mentioned spring serves to force said carrier against said stop means in a direction opposed to said second spring as the presser foot

is urged against work of uniform thickness, said presser foot being held against the work by the full force of said first mentioned spring.

9. In a sewing machine, a work support, a presser bar, a spring urging said presser bar downwardly, a shank attached to the lower end of said bar, a carrier shiftably mounted on said shank, stop means for limiting the movement of said carrier in each direction on said shank, a second spring urging said carrier in one direction relative to the shank, a presser foot pivotally mounted on said carrier, said first mentioned spring being stronger than said second spring, the parts being so constructed and arranged that said first-mentioned spring serves to force said carrier against said stop means in a direction opposed to said second spring as the presser foot is urged against work of uniform thickness, said presser foot being held against the work by the full force of said first mentioned spring, and means operable at will for offsetting the force of said first mentioned spring while allowing said second spring to urge said presser foot against the work.

10. In a lockstitch sewing machine having a work support, a reciprocable needle and a rotary hook, means for facilitating the locking of the end of a seam which comprises a presser foot, a plurality of springs normally acting simultaneously in series relation to urge said presser foot against work on said support, one of said springs being stronger than another and normally exerting its full effect upon said presser foot, and means operable at will for offsetting the action of only said stronger spring.

11. In a lockstitch sewing machine having a work support, a reciprocable needle and a rotary

hook, means for facilitating the locking of the end of a seam which comprises a presser foot, a plurality of springs alternately effective for urging said presser foot against work on said support, one of said springs being arranged to exert a greater force than another, and means under control of the operator for rendering either of said springs ineffective at will in the course of stitching work of uniform thickness.

10 12. In a lockstitch sewing machine having a work support, a reciprocable needle and a rotary hook, means for facilitating the locking of the end of a seam which comprises a presser foot, a plurality of springs alternately effective for urging said presser foot against work on said support, one of said springs being arranged to exert a greater force than another, means for varying the force exerted by said one spring, and means under control of the operator for rendering either of said springs ineffective at will in the course of stitching work of uniform thickness.

15 13. In a sewing machine, a work support, a presser bar, a spring urging said presser bar downwardly, a shank attached to the lower end of said bar, a member slidably mounted on said shank, a spring urging said member downwardly on said shank, a presser foot pivotally mounted on said member, said presser foot having upwardly extending ears cooperating with surfaces on said shank to guide the presser foot in its movements relative to the shank, said first mentioned spring being stronger than the second and normally exerting its full effect upon said presser foot, and means operable at will for offsetting the action of only said first mentioned spring.

30 35 CHARLES F. RUBEL.
